Attorney

UNITED STATES PATENT OFFICE.

HARVEY B. LINDSAY, OF OAKLAND, CALIFORNIA, ASSIGNOR TO THE DRY-ZERO CORPORATION, OF OAKLAND, CALIFORNIA, A CORPORATION OF CALIFORNIA.

REFRIGERATOR AND ICE MACHINE.

Application filed January 25, 1922. Serial No. 531,556.

To all whom it may concern:

Be it known that I, HARVEY B. LINDSAY, a citizen of the United States, residing at Oakland, in the county of Alameda and State of California, have invented certain new and useful Improvements in Refrigerators and Ice Machines, of which the following is a specification.

My invention is an improved overhead 10 refrigerator and ice machine in which ice is frozen in small cubes to be placed in drinking glasses to make icewater.

My invention is an embodiment of and improvement on my refrigerator disclosed 15 in my co-pending application filed August 9, 1921, Serial Number 490,904 now Patent Number 1,487,529, Dec. 5, 1922.

Referring to the annexed drawing in which my invention is illustrated and which 20 forms a part of this specification:

Figure 1 is a longitudinal vertical section of my invention.

Figure 2 is a perspective view of the ice mold drawer.

25 Figure 3 is a view showing the drawer opening through the side wall of the refrigerator.

In the drawing 1 indicates the body of my refrigerator and 2 a turret upstanding 30 from the upper wall of said body. A receptacle 3 is formed with a body 4 and with extensions 5 and 6 at the bottom and the respective sides of said body, said body fitting the turret 2 and said extensions extending 35 under the upper wall of the refrigerator body 1 at the sides of said turret respectively. The upper walls of the extensions 5 and 6 incline upwardly to the receptacle body 4. The body 4 of the receptacle 3 has a hopper 7 in the top thereof which extends above the turret, through 40 which hopper brine 8 and ice 9 are placed in the receptacle. The refrigerator body has a door 10 through which articles are placed in the body below the receptacle 3 or taken out of the receptacle.

Chambers 11 and 12 extend transversely through the extensions 5 and 6 respectively into which chambers are introduced ice drawers 13 and 14 respectively, which drawers are constructed with a plurality of cubic ice molds 15 of a size smaller than a drinking glass. The molds 15 are filled with water before the drawers 13 and 14 are introduced in the chambers 11 and 12.

The colder brine being at the bottom of the receptacle 3 will have its temperature raised above that of the body of the brine by the heat of the articles in the refrigerator. This warmed brine will now rise to 60 the top of the receptacle 3 and upwardly along the inclined walls of the extensions to the ice compartment, being replaced by the colder upper strata of brine. This circulation is continued to lower the temperature of the refrigerator and freezes the water in the molds 15 into ice cubes which are placed in drinking glasses.

The molds may also be formed in different shapes, to conform to different requirements.

Having described my invention, I claim:

A refrigerator and ice machine comprising a refrigerator body adapted to receive articles of food, a receptacle in the upper 75 part of said body in which is placed brine and ice, a chamber extending through said receptacle and about which the brine circulates and a drawer constructed with a plurality of transverse and longitudinal 80 walls, which drawer when filled with water is introduced in said chamber from the outside of the refrigerator, said drawer having a flange on its outer face adapted to engage the outer surface of the refrigerator, said 85 flange serving as a stop for the drawer and also as an insulating means.

In testimony whereof I affix my signature.

HARVEY B. LINDSAY.
